UNITED STATES PATENT OFFICE.

MATTHEW ANDREW JORSCH, OF JANEVILLE, WISCONSIN.

BUILDING WALL.

Application filed August 29, 1924. Serial No. 734,953.

This invention relates to building walls, designed with special reference to heat insulation.

The object of the invention is to construct a wall which will be inexpensive yet durable, and which will provide an effective insulation to prevent the exchange of heat between the interior of the building and the outside atmosphere. The wall is constructed in such a manner as to prevent convectional currents in the space between the sheathing and plaster, and thus prevent the formation of sweat and its undesirable consequences.

The structure consists primarily in securing within the wall an intermediate lining, preferably of corrugated pasteboard or other fibrous material, and so secured as to form a series of comparatively small pockets adjacent the laths and plaster, whereby convectional currents are prevented. The lining may be used in the side walls of the building or between the upper story and the attic floor.

The structural details of the invention will be more particularly described in connection with the accompanying drawing, in which—

Figure 1 is an elevation of a portion of a wall embodying one form of the invention, with the plaster and some of the laths removed.

Figure 2 is a sectional view of the completed wall taken on the line 2—2 of Figure 1.

Figure 3 is a horizontal section taken on the line 3—3 of Figure 1.

Figure 4 shows a portion of an unfinished wall of modified construction, having inserts pasted within it to form additional air spaces.

Figure 5 is a fragmentary cross section of the completed wall taken on the line 5—5 of Figure 4.

Figure 6 is perspective view of a portion of one of the inserts with pasting strips attached thereto.

As shown in the drawing, the wall comprises the usual studs 5, on the outside of which are secured sheathing 6 and siding 7, separated by building paper 8. On the inside of the studs 5 are secured the laths 9 and plaster 10. In carrying out my invention, I provide an intermediate lining 11, which consists preferably of corrugated pasteboard made up of two or more layers

of flat paper separated by corrugated paper. This intermediate lining is made up of separate sections extending from side to side between the studs, and separated every 60 1, 2, 3, or 4 feet by headers 12 formed of the same material. In applying the lining to the studs, it is cut to such a width that the opposite side edges may be bent to form side flanges 13, with the bending lines 14 65 separated by a distance equal to the distance between the faces of the adjacent studs. These side flanges 13 are secured to the studs immediately in rear of the laths 9, and may, if desired, be held by cleats 15. 70 The adjacent ends of the lining sections are similarly bent to form horizontal flanges 16 extending from side to side of the space between the studs, the abutting flanges of two adjacent sections forming the headers. The 75 corners 17, which are formed between the flanges 13 and 16, may be bent inwardly toward each other and form a reinforcement for the flanges 16, to hold the same perpendicular to the body portions of the lining. 80

The cost of the additional lining 11 is comparatively small and its application to the studs in the manner described and shown is very simple and easily accomplished. The several sections of lining may 85 be cut to the desired length, so that the headers 12 will be a suitable distance apart to prevent the formation of convectional currents due to the heat inside the wall, while the dead air spaces within the paper 90 itself form an effective insulation between the moderate degree of heat inside the pockets formed by the headers and the space next to the sheathing. Thus, very little heat reaches the sheathing, and consequently the formation of sweat or frost on the inside thereof will be substantially prevented. The lining 11 is therefore kept dry, as well as the plaster.

In the construction shown in Figures 4, 100 5 and 6, each of the pockets formed by the lining members 11 is subdivided by a plurality of inserts 18 formed of the same kind of material as the lining 11. Each of these inserts 18 is bent to form oppositely disposed 105 flanges 19 of approximately half the width of the flanges 13 and 16, and the several flanges 19 are connected to each other and to the flanges 16 by pasting strips 20. Other pasting strips 21 are provided for attaching 110 the inserts to the flanges 13 adjacent the studs 5. Arranged in this manner, the

pocket formed by the insert 11 is divided substantially mid-way between the bottom of the same and the lath and plaster, while the flanges 19 divide the pocket vertically 5 into a number of smaller sections, which forms a more effective heat insulation. These inserts 18 may be used or omitted, according to the conditions under which the building is constructed, and the character of the 10 building.

Although I have shown the specific construction by means of which the invention may be embodied, it is to be understood that this is merely illustrative, and that modifications may be made in the kind of paper or other fibrous material from which the lining is made, as well as the specific manner in which it is attached to the studs without departing from the spirit of the invention or sacrificing any of the advantages thereof.

What is claimed is:

1. In a building wall, the combination with studs having the outer and inner portions of the wall secured to their opposite edges, of an intermediate lining spaced from the outer and inner portions of the wall and made up of sections laid end to end one above the other between the studs, the side 25 edges of the sections being bent at right angles and secured to the opposed faces of the studs, the adjacent ends of the sections being also bent at right angles to form horizontal flanges which abut against each other 30 and bridge the space between the lining and the inner portion of the wall to form enclosed separate pockets, the corners formed by the folding of the sides and ends being folded behind the abutting flanges to reinforce the same and maintain their faces in 35 abutting relation.

2. In a building wall, the combination

with studs having the outer and inner portions of the wall secured to their opposite edges, of an intermediate lining spaced from 45 the outer and inner portions of the wall composed of paper having a plurality of flat sheets separated by a corrugated sheet, said lining being made up of sections laid end to end one above the other in the several spaces 50 between the studs, the side edges of the sections being bent at right angles and secured to the opposed faces of the studs, the adjacent ends of the sections being turned inwardly to form horizontal flanges which 55 abut against each other and bridge the space between the lining and the inner portion of the wall to form separate enclosed pockets, the corners formed by the folding of the sides and ends being folded behind the horizontal flanges to reinforce the same and maintain their adjacent faces in abutting 60 relation.

3. In a building wall, the combination with 65 studs having outer and inner wall sections secured to their opposite edges, of an intermediate lining secured to the studs and spaced from the outer and inner wall sections and made up of sections having their adjacent edges turned inwardly to form 70 flanges which abut against each other and bridge the space between the lining and the inner sections of the wall to form separate enclosed pockets, a plurality of inserts in each pocket subdividing it in thickness and 75 height to form additional dead air spaces, and pasting strips on the adjacent edges of said inserts for securing the said inserts in position.

In testimony, that I claim the foregoing as my own, I have hereto affixed my signature.

MATTHEW ANDREW JORSCH.
